US00D691663S

(12) **United States Design Patent**
Ashida et al.

(10) **Patent No.:** US D691,663 S
(45) **Date of Patent:** ** Oct. 15, 2013

(54) **UPPER HOUSING OF CONTROLLER FOR ELECTRONIC COMPUTER**

(71) Applicant: **Nintendo Co., Ltd.**, Kyoto (JP)

(72) Inventors: **Kenichiro Ashida**, Kyoto (JP); **Masato Ibuki**, Kyoto (JP); **Shinji Yamamoto**, Kyoto (JP); **Fumiyo Yoshi Suetake**, Kyoto (JP); **Akiko Suga**, Kyoto (JP); **Naoya Yamamoto**, Kyoto (JP); **Hitoshi Tsuchiya**, Kyoto (JP); **Junji Takamoto**, Kyoto (JP); **Daisuke Kumazaki**, Kyoto (JP); **Yositomo Gotou**, Kyoto (JP); **Takanori Okamura**, Kyoto (JP)

(73) Assignee: **Nintendo Co., Ltd.**, Kyoto (JP)

(**) Term: **14 Years**

(21) Appl. No.: **29/448,050**

(22) Filed: **Mar. 8, 2013**

Related U.S. Application Data

(63) Continuation of application No. 29/407,809, filed on Dec. 2, 2011, now Pat. No. Des. 681,128.

(57) **CLAIM**

The ornamental design for an upper housing of controller for electronic computer, as shown and described.

DESCRIPTION

FIG. 1 is front, right and bottom perspective view of an upper housing of controller for electronic computer showing an embodiment of our new design;

FIG. 2 is rear, left and top perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

The subject matter shown in dashed lines is for reference purposes only, and forms no part of the claimed invention.

1 Claim, 6 Drawing Sheets
